UNITED STATES PATENT OFFICE.

JOSEPHINE HARRISON, OF DENVER, COLORADO.

BOOK-REST.

1,219,393.

Specification of Letters Patent. Patented Mar. 13, 1917.

Application filed October 25, 1913. Serial No. 797,340.

To all whom it may concern:

Be it known that I, JOSEPHINE HARRISON, a citizen of the United States, residing at Denver, in the county of Denver and State 5 of Colorado, have invented certain new and useful Improvements in Book-Rests; and I do hereby declare the following to be a full, clear, and exact description of the invention, such as will enable others skilled in the art 10 to which it appertains to make and use the same.

My invention relates to furniture, and more especially to book rests; and the object of the same is to provide a simple and inexpensive 15 book rest whose parts are capable of folding into small compass for storage and transportation, whose table may be adjusted in one of three working positions or laid out flat over the brace, and whose ledge is useful for holding the books open whatever 20 the position of the table.

With these and other objects in view the invention comprises certain novel constructions, combinations and arrangements of 25 parts as will be hereinafter more fully described and claimed, being shown in the accompanying drawings in which similar characters indicate corresponding parts and in which—

30 Figure 1 is an isometric view of my invention in use, a fragment of a book being shown in position thereon, a variation of position being shown in dotted lines.

Fig. 2 is a side elevation of my invention 35 when folded or collapsed.

In constructing my invention I provide a base 1 having rising therefrom and solidly attached thereto or formed integral therewith, as desired, a rib 2. Attached to rib 2 40 by suitable folding means, as by hinges 3, I provide table 4. Foldingly attached to base 1, as by hinges 5, I provide brace 6 for bracing or supporting table 4 at the desired angle, as clearly illustrated in the drawings.

45 Brace 6 is hinged at its front corner to base 1 in such a manner that it cannot be moved to the rear beyond the position shown in dotted lines in Fig. 1, the same being approximately perpendicular to base 1. As 50 clearly appears in the drawings, when brace 6 has been raised to the dotted line position, its edge adjacent the hinges contacts with base 1 like a knuckle joint and prevents further outward movement.

55 Table 4 is of sufficient length to extend from the rib 2, where it is hinged, to the

top edge of brace 6 when brace 6 is in its dotted line position, *i. e.* approximately perpendicular to base 1.

It will thus be apparent that the table 4 60 cannot be collapsed by the movement of brace 6 to the rear because the brace 6 cannot move beyond a point where it will support the table 4.

One or more notches or grooves 7 may be 65 provided if desired in the bottom or back of table 4 for engaging the upper edge of brace 6, but this is not part of my invention for in practice it will usually be found unnecessary, the weight of table 4 being sufficient, when resting upon the upper edge of brace 6, to hold brace 6 in any desired position in which it is placed in contact with table 4. It is obvious that no notches or other special engaging means are required 70 to maintain table 4 and brace 6 in engagement in either the full line or dotted line positions shown in Fig. 1. The same is true of other positions in which these parts may be brought into engagement unless the surfaces of the parts are made very smooth in which case notches or grooves may be employed to maintain the engagement of these 75 parts in such other positions.

I also provide a ledge or book retaining 80 member 8 foldingly attached, as by hinges 9, to base 1 at a suitable distance from rib 2, and here again the hinge is so located that it acts like a knuckle joint so as to cause the edge of the ledge to rest upon base 1 and 85 prevent it from opening beyond position shown at Fig. 1.

It will be understood that brace 6 is so proportioned to the space between rib 2 and hinge 5 as to fold therein as clearly shown 90 at Fig. 2 and that rib 2 is of sufficient height as also clearly shown at Fig. 2.

It will also be understood that the ledge 8 is so proportioned to the space between rib 100 2 and hinge 9 as to fold therein as clearly shown at Fig. 2.

When the parts are adjusted as shown in Fig. 1 it is apparent that a book laid open upon table 4 will be supported thereby in 105 an inclined position, the degree of incline being determined by the position of brace 6 so that by moving brace 6 the table 4 and the book carried thereby will be raised or lowered to the desired incline for reading. 110

It will also be apparent that the ledge 8 will hold the book in place upon table 4.

and will also keep the leaves of the book from turning.

Also it will be apparent that papers and similar articles not in ordinary book form 5 may be handled upon this device in a similar manner and with result as above described.

When not in use the parts are collapsed or 10 folded into compact form shown in Fig. 2, which is made possible by the construction above described.

What I claim is:

A book rest, comprising a base, a longitudinal rib secured to the base, a table hinged 15 to the rib and foldable parallel with the base, said rib being parallel with and spaced from one longitudinal edge of the base to

provide a support for the edge of the book directly on the base, between the rib and said longitudinal edge, a brace and a book 20 retaining strip hinged on opposite longitudinal edges of the base and having their movement limited to approximately ninety degrees, the brace and strip being foldable toward each other on the base with their 25 free edges adjacent opposite sides of the rib, said brace being adapted to maintain the table in operative position.

In testimony whereof, I affix my signature in presence of two witnesses.

JOSEPHINE HARRISON.
